Application February 3, 1949, Serial No. 74,293

3 Claims. (Cl. 100—125)

1

This invention relates to a novel dewatering press and more particularly, to a continuous-flow press for removing water from such material as bark, bagasse, peat moss and the like.

Raw bark and other material used as fuel usually has a high moisture content of from 70% to 80%, requiring a substantial reduction in moisture content if the material is to function efficiently for fuel purposes. It is a general object of the present invention to provide a dewatering press which will serve to effectively and efficiently reduce the water content of material of the character indicated which it is desired to employ for fuel purposes, as well as many other types of material whose effective utilization depends upon reduction of water content, such as wood chips and wood shavings employed as starting materials in the fabrication of fiberboard, wallboard and the like.

Another object of the invention is the provision of a dewatering press which is constructed and arranged in such a manner that the removal of water thereby will be accomplished in a smooth and continuous operation, the material of high water content being fed continuously to the press at one end and the material of reduced water content being discharged continuously at the other end.

A further object of the invention is the provision of a dewatering press of the character described having a receiving chamber, a compression chamber and an intermediate chamber provided with slots or apertures allowing drainage of water from the material being treated without interfering with the continuous operation of the press.

An additional object of the invention is the provision of a dewatering press having a tapered screw with diminishing pitch arranged to compress the material being treated within a compression chamber having forwardly convergent walls with longitudinal grooves formed therein in order to achieve high compression and efficient dewatering, the walls of the compression chamber being further provided with clog-free apertures for draining the water removed from the material being treated.

Another feature of the invention resides in a novel arrangement for minimizing wear and extending the life of the press by providing adjustable and replaceable inserts extending along the longitudinal grooves of the compression chamber, each insert being mounted between an adjacent pair of segments forming the body of the compression chamber and the inserts being ad-

2

justable externally of the compression chamber, as by means of bolts intersecuring the chamber segments.

The foregoing objects as well as additional objects and advantages of the invention will be readily apparent in the course of the following detailed description taken in connection with the accompanying drawings which illustrate a preferred embodiment of the invention, and wherein:

Fig. 1 is a top plan view of a dewatering press embodying the features of the invention;

Fig. 2 is a sectional view taken on line 2—2 of Fig. 1;

Fig. 3 is a vertical section taken on line 3—3 of Fig. 1;

Fig. 4 is an enlarged detail view illustrating the construction of the compression chamber or throat and the intermediate chamber or throat base ring;

Fig. 5 is a sectional view taken on line 5—5 of Fig. 4;

Fig. 6 is a sectional view taken on line 6—6 of Fig. 4;

Fig. 7 is a fragmentary detail view taken on line 7—7 of Fig. 6 showing the arrangement of the adjustable groove inserts between adjacent throat segments;

Fig. 8 is a fragmentary detail view taken on line 8—8 of Fig. 6 illustrating the formation of the clog-free apertures in the throat segments; and

Fig. 9 is a sectional view taken on line 9—9 of Fig. 4 illustrating the construction of an adjustable discharge device which may be incorporated in the dewatering press.

Referring now to the drawings in greater detail, a uniform flow of material through the press is assured in any suitable manner, as by means of a twin screw feed 10, 10 arranged in hopper 11 and driven by means of motor 12 through belt 13 and gears 14. The material being fed to the press undergoes preliminary compression in hopper 11. Water removed from the material in hopper 11 is drained through a plurality of small apertures 15 in the bottom wall 16 of said hopper, as shown in Fig. 2, and received in an inclined trough 17 communicating with the drainage system of the press.

The material passes from hopper 11 into the receiving chamber 18 of the press which is preferably provided with a removable cover 19 to make said receiving chamber accessible for cleaning purposes. A helical compression element or screw 20 extends forwardly within receiving

chamber 18 and within the remaining portion of the press. Shaft portion 20a of screw 20 is rotatably mounted in a fixed bearing member or housing 21 as by means of roller bearings 22 and thrust bearing 23. Suitable oil retainers 24 are also provided at either end of bearing member 21 and a water throw-off ring 25 is mounted on shaft 20a between said bearing member and the adjacent end of receiving chamber 18 to prevent the possibility of any water entering the bearing member. Screw 20 is driven at the desired rate of revolution from an external power source (not shown).

The rotation of screw 20 will carry the material being dewatered into the anterior portion of the press comprising the compression chamber or throat member 26 and the intermediate chamber or throat base ring 27, most of the compression of the material occurring in the throat member 26 and the primary function of the intermediate chamber or base ring 27 being to afford drainage of the bulk of the water expressed from the material in said throat member. Accordingly, in the preferred embodiment of the invention, both throat member 26 and throat base ring 27 are formed as frusto-conical sections having forwardly convergent inner walls so that the preponderant flow of water expressed from the material in said throat member will be rearwardly to the throat base ring 27.

As clearly shown in Figs. 3, 4 and 5, throat base ring 27 is provided with a plurality of drainage ports or slots 28. In order to provide for efficient discharge of water and simultaneously prevent clogging, slots 28 are preferably formed of uniform width inwardly for a relatively short distance as shown at 28a and then of gradually increasing width outwardly as shown at 28b in Figs. 4 and 5.

In order to assure efficient compression and maximum dewatering of the material being treated the anterior end of screw 20, i. e. the portion of said screw fitting within the throat base ring 27 and throat member 26, is formed with diminishing diameter and diminishing pitch so as to fit snugly within the respective portions of the press, as clearly shown in Fig. 3. Base ring 27 and throat member 26 are provided with preferably angular spaced longitudinal grooves or recesses 27a and 26a defining retaining surfaces 27b and 26b against which the material being treated can be crushed and compacted for maximum compression and removal of water as screw 20 rotates.

Since most of the compression of material occurs in compression chamber or throat member 26 the greatest amount of wear results therein, particularly along the retaining surfaces 26b of grooves 26a. The life of throat member 26 may be greatly extended by forming said throat member from a plurality of segments 29 interconnectable as by means of bolts 30, as shown in Figs. 6 and 7. Special hardened inserts or facings may be interposed between adjacent segments 29 to serve as the retaining surfaces 26b. Said inserts 26b may be adjusted periodically with continued use to compensate for attendant wear as by means of elongated mounting holes 31 which receive the segment mounting bolts 30. When no longer adjustable, worn inserts may be replaced by fresh inserts by dismantling throat segments 29 without requiring a completely new throat member 26.

While the bulk of the water expressed from the material in throat member 26 drains from

the press through slots 28 of base ring 27 provision is also made in throat member 26 for drainage in the form of a plurality of rows of clog-free apertures 32 formed in each throat segment 29. Drainage apertures 32 are preferably formed with an innermost portion 32a of relatively small diameter opening into an outermost countersunk portion 32b of relatively large diameter, as best shown in Fig. 8, in order to provide efficient drainage and prevent clogging while simultaneously preventing any of the material being treated from passing through said apertures. For example with a throat member of $1\frac{1}{8}$ " wall thickness a drainage aperture having an innermost portion of $\frac{1}{4}$ " diameter and $\frac{1}{16}$ " depth and an outermost countersunk portion of $\frac{3}{4}$ " diameter has proven satisfactory. The depth of innermost portion 32a is preferably slightly less than the diameter thereof.

Throat member 26 is surrounded by a drainage jacket 33 communicating with a main drainage trough 34 having its bottom inclined downwardly toward a centrally disposed outlet pipe 35 to assure continuous automatic drainage. Inclined trough 17 also communicates with main trough 34, as shown in Fig. 2.

An adjustable pressure-relieving discharge device or "rattrap" is preferably provided for the dewatering press. The discharge device comprises a pair of side plates 36, a bottom plate 37, and a hinge plate 38 swingable mounted between said side plates at 39. The volume of the discharge device and the downward pressure of hinge plate 38 may be varied to control the discharge rate of the dewatered material to a certain extent and to expel residual water through perforations 40 in side plate 36, bottom plate 37 and hinge plate 38. The extent of depression or elevation of hinge plate 38 may be controlled by a threaded handle element 41 mounted on support 42. A compression spring 43 is interposed between hinge plate 38 and a cup-member 44 carried by handle element 41 and a return tension spring 45 operates to elevate said hinge plate when said handle element is raised. Hinge plate 38 will react to a pulsating flow of material issuing from compression chamber 26 and by exerting pressure on the material will express residual water therefrom through perforations 40. Drainage jacket 33 extends into the region of discharge device 35.

Since certain modifications may be made in the dewatering press of the present invention without departing from the scope thereof, it is intended that all matter contained in the foregoing specification and shown in the accompanying drawings be interpreted merely as illustrative and not in a limiting sense.

What is claimed is:

1. A continuous-flow dewatering press comprising a receiving chamber, feeding means therefor, a compression chamber having walls converging toward the outlet end thereof, an intermediate chamber having walls converging forwardly toward said compression chamber and communicating therewith and a rotatable helical compression element extending within said chambers, said compression chamber having a plurality of drainage apertures for removal of water therefrom, said intermediate chamber having a plurality of drainage slots whereby water expressed from material within said compression chamber will flow continuously toward said intermediate chamber and the drainage slots thereof, said compression chamber having a plurality of spaced longitudinal grooves defining retaining

surfaces for compressing, compacting and dewatering material urged thereagainst by said rotatable compression element, said compression chamber being formed from a plurality of chamber segments, wear-resistant inserts adjustably engageable between adjacent chamber segments and coextensive with each of said longitudinal grooves, and a discharge chamber communicating with said compression chamber, said discharge chamber having a hinge plate adjustably and resiliently mounted for exerting variable pressure on the material issuing from said compression chamber, said discharge chamber and said hinge plate having a plurality of perforations for removal of residual water from said issuing material.

2. In combination with a continuous-flow dewatering press having a compression chamber, a discharge chamber communicating with said compression chamber, said discharge chamber comprising a pair of perforated side plates, a perforated bottom plate, a perforated hinge plate swingably mounted between said side plates, a supporting bracket, a handle element threadedly engaged upon said supporting bracket, a cup member carried at the lower end of said handle element, a compression spring interposed between said cup member and said hinge plate, and a return spring secured between said hinge plate and said supporting bracket, whereby to vary the volume and flow of material through said discharge chamber and remove residual moisture therefrom.

3. In combination with a continuous-flow dewatering press having a compression chamber, a discharge chamber communicating with said compression chamber, the discharge chamber comprising a pair of perforated side plates, a perforated bottom plate, a perforated hinge plate swingably mounted between the side plates and

10
